UNITED STATES PATENT OFFICE.

BARNEY WALLER, OF PHILADELPHIA, PENNSYLVANIA.

INDOOR BASEBALL GAME.

Application filed April 18, 1922. Serial No. 554,883.

To all whom it may concern:

Be it known that I, BARNEY WALLER, a citizen of the United States, residing at Philadelphia, in the county of Philadelphia and State of Pennsylvania, have invented 5 certain new and useful Improvements in Indoor Baseball Games, of which the following is a specification.

My invention relates to improvements in 10 game boards for playing indoor base ball and its main object is to provide a board representing a base ball field, together with eighteen manikins or players and a spinning top, which is designed to indicate 15 the different moves to be made on the board.

By the use of these paraphernalia the game may be played between two contesting 20 parties in full imitation of an outdoor base ball game including all the excitement and suspense connected therewith.

For this purpose the game board represents a diamond with all bases thereon and the manikins are preferably numbered 1 to 9 for each side and colored in a different 25 manner to distinguish one team from the other. Each contestant takes nine of these men, representing, for instance, a home team and a visitor's team and by spinning the top, which has preferably eight faces on it 30 all marked differently, indicating the different chances in a base ball game, the moves of the manikins on the board will be given on the uppermost face of the top, when the latter has stopped spinning.

35 In the accompanying drawings:

Figure 1 is a top plan view of the game board showing the diamond;

Fig. 2 is a section on the line 2—2 of Fig. 1;

40 Fig. 3 is a perspective view of the spinning top;

Fig. 4 is a development of the side faces of the top;

Fig. 5 shows a side elevation of one of 45 the manikins to be used;

Fig. 6 represents a score board of the general character used for base ball games.

The game board consists of a frame 10 wherein is mounted a flat bottom 11, on 50 which the plan of a base ball field is marked. The frame is about thirty inches square and the outfield 12 is preferably painted green, while the infield has the base paths 13 painted light buff or clay color 55 with the enclosed portion 14 also painted green. The bases 15, 16, 17 and 18 are

painted white and the entire board is preferably covered by plate glass. Along the right and left hand sides, respectively, are the dug outs 19 and 20 for the home and 60 visiting teams and in the dug outs the nine manikins 21 for the contesting sides are positioned in numerical order from the rear end of the field. Their respective positions are marked in the dug outs, as at 22, and 65 each manikin also carries a number from 1 to 9.

The numerals 15, 16, and 17 denote the first, second and third bases, respectively, and the numeral 18 denotes the home plate. 70

Two boxes 23 and 24 are provided for the coaches. The manikins representing the players are positioned near the boxes 23, 24, 25 and 26 and the right, central and left fielders at 27, 28 and 29, respectively, 75 while the pitcher as usual is placed at 30 and the batter at 31.

A spinning top shown in Figs. 3 and 4 has the general shape of a toy of this character, that is to say it has a point 32, a 80 handle 33 and a body 34 and is preferably made of hickory wood. A suitable size of the top is about two inches in length and the body one inch in thickness. The latter is of octagonal cross section providing 85 eight flat surfaces which are marked as indicated in Fig. 4. The first face 35 of the top is marked B-B which stands for "Base on balls"; the face 36 is marked 2B-H which stands for "Two base hit"; the face 37 is 90 marked D-P meaning "Double play"; the face 38 is marked S-O which stands for "Strike out"; the face 39 is marked 1B-H which stands for "One base hit"; the face 40 is marked O-S which means "Out stealing"; the face 41 is marked F-O which means "Fly out," and the last face 42 is marked O-F which stands for "Out at first base."

The players, as already described, are represented by eighteen manikins 21 of which nine represent the home team and nine the visitor's team. These manikins are intended to represent the ball players and about one and one-half inches high for a game board thirty inches by thirty inches and the manikins are made of pewter or similar material and constructed with a foot plate 43 so that they will be able to stand in the positions designed for them on the board and each of 105 the foot plates carries a number from 1 to 9 for each team. 110

The game is played in the following manner: Supposing the manikins of the home team wear gray colored uniforms and the visitor's team wear black uniforms, the gray 5 colored men of the home team are positioned in the proper order on the board, that is to say, No. 1 on first base, as at 23; No. 2 second base, as at 24; No. 3 center field, as at 28; No. 4 right field, as at 27; No. 5 left 10 field, as at 29; No. 6 third base, as at 26; No. 7 short stop, as at 25; No. 8 catcher on the home plate 18, and No. 9 pitcher in the center, as at 30.

The line up of the visiting team may be as 15 follows: Placed in a right hand dug out according to the numbers designated at 22, namely, No. 1 left field, No. 2 second base, No. 3 center field; No. 4 right field; No. 5 third base; No. 6 short stop; No. 7 first base; 20 No. 8 catcher and No. 9 pitcher.

The manikin carrying No. 1 of the visiting team is thereupon placed as the batter, at 31, in front of the home plate 18 and the top is now spun and as soon as it has stopped 25 spinning the indication on the uppermost face of the top is noted, and supposing the marking shows B-B which stands for "Base on balls," man No. 1 is moved to first base, similarly to what would take place in a regular 30 outdoor base ball game. Man No. 2 is positioned to bat at the home plate and the top is again spun. Supposing that it registers 2B-H, which means "Two base hit," man No. 1 is then moved from first base to 35 third base and the batter moves to second base while man No. 3 of the visiting team is placed to bat. The top is now again spun and supposing that it registers D-P which means "Double play," the batter and the 40 man on third base are then declared "out" and these two men have to be removed to the dug out while man No. 4 of the visiting team is placed in position to bat. Again spinning the top which now might register O-F, 45 which means "Out at first base," three men will then be out and the visiting side retired. The home team is now placed in its dug out and the visitor's team in the field, as already described. In this manner with the proper 50 line up, a game can be played with the teams representing the American and National leagues or any independent team.

If during the play the top registers O-S, it is called a foul, as it indicates "Out stealing," there being no one on base, this play 55 cannot be executed for which reason it is called a foul and the first two fouls are called strikes. This also applies to D-P indicating "Double play" under the same circumstances.

All base runners advance, when the top registers O-F which indicates "Out at first" or sacrifices, when the batter is out. No base runner advances when the top registers F-O indicating "Fly out." No base runner scores 60 from second base on a single. When the base runner is on second and top registers 2B-H indicating "Two base hit," a runner scores from second.

In Fig. 6 is shown a score board of the 70 usual type which should accompany the gameboard for marking. This shows the visitor's and home team and columns for the nine innings marked in numerical order and also three columns marked R, H and E, respectively, denoting runs, hits and errors.

In addition to the score board for the 75 innings, box scores for each team may also be provided as part of the game, having columns for "At bases;" "Hits;" "Runs;" 80 "Base on balls;" "Strike out;" "Out stealing;" "Double play;" "Out on first;" and "Fly out."

Having thus described the invention, what 85 is claimed as new is:

In a base ball game apparatus, the combination with sets of marked manikins, and a spinning top adapted to indicate different plays; of a flat board, an upstanding frame 90 around said board defining the field, and a plate glass covering the field mounted in said frame; said field having the base paths of the diamond delineated thereon and the bases represented by a different delineation 95 on said base paths, and a dug out in said field along the right and left sides of the frame and adjacent the rear corners thereof, said dug outs having indicia corresponding to the marking of the manikins in order that the manikins may be placed in a certain 100 order in said dug outs.

In testimony whereof I affix my signature.

BARNEY WALLER. [L. s.]
